UNITED STATES PATENT OFFICE.

WILLIAM M. BARNES, OF PHILADELPHIA, PENNSYLVANIA.

GOODS-SUPPORT FOR CLOTHES-DRYING MACHINES.

SPECIFICATION forming part of Letters Patent No. 746,659, dated December 15, 1903.

Application filed June 29, 1903. Serial No. 163,491. (No model.)

To all whom it may concern:

Be it known that I, WILLIAM M. BARNES, a citizen of the United States, residing at Philadelphia, county of Philadelphia and State of Pennsylvania, have invented a new and useful Improvement in Goods-Supports for Clothes-Drying Machines, of which the following is a full, clear, and exact description, reference being had to the accompanying drawings, which form a part of this specification.

My invention relates to certain improvements in goods-supports for that class of drying-machines which are illustrated, described, and claimed in Letters Patent No. 684,776, issued to me October 22, 1901. In that patent the support for the goods to be dried consisted of laterally-projecting pins. With this character of support it is impossible to separate the goods into groups with certainty. With certain classes of goods—for instance, new collars—it is essential that a certain group of collars, one dozen, shall be held together from the time they are given to the laundry until they are boxed. Where they are hung up upon independent pins, it is practically impossible to accomplish this result with any certainty. It is to render certain this result with my clothes-drying machine of my Patent No. 684,776 that I have devised the goods-support which forms my present invention. This improvement, broadly considered, consists in connecting to the conveyer preferably a hook, a bar, or two bars secured together, each bar supporting a plurality of supports upon which the garments may be placed.

My invention also consists in certain important details, which hereinafter will be more fully explained.

In the drawings, Figure 1 is a side elevation with parts assembled. Fig. 2 is a detail side elevation with parts in position for stripping goods. Fig. 3 is a section on line 3 3, Fig. 1. Fig. 4 is top plan view of carrier. Fig. 5 is a bottom plan view of carrier.

A is the conveyer, suspended by rollers *a a* from a track T, all as in my previous patent No. 684,776. From the conveyer A extends at intervals a shank *b*, at the end of which is a hook *B*.

C are bars, preferably of wood, connected

together by the plate C', having the eye *c* upon it, the hook *B* being adapted to engage the eye *c*. On the under surface of each bar C is a groove *d*, in which is slidably mounted the plate D, having the projecting portion *d'*, passing through the slot *d²* in the bars C. To the upper end of this projecting portion *d'* is attached the lug or head *d³*, by means of which, within the limit of slot *d²*, the plate D may be moved along the bar C. Secured to the plates D are a number of goods-supports *d³*, which, as shown, are angular in form. Secured to the bars C are a plurality of hoops or loops *d⁴*. In the movement of the plates D the goods-supports *d³* may be brought in such position that the vertical portion is in alinement with loops *d⁴* (full lines, Fig. 1,) when the goods may be freely placed upon and carried by the supports *d³*. They then may be moved to the dotted-line position shown, Fig. 1, when the goods are secured from falling from the goods-supports. To release the goods, the plates D are moved in the reverse position until the goods-supports pass through the loops, (see Fig. 2,) in which case in the movement from the first-mentioned position to this position the goods will be stripped off.

As may readily be seen, with the construction just described a certain batch of collars—twelve, for instance—sufficient for a box, may be placed after starching upon one of these compound goods-supports. The compound support is detachably secured to the conveyer, and the goods treated from the time they are starched until they reach the final operation entirely separate from any other batch. This enables the work of the operatives to be determined and also a given batch of collars to be maintained together. Of course after drying the operator merely releases the compound support from the conveyer.

Having now fully described my invention, what I claim, and desire to protect by Letters Patent, is—

1. In a drying-machine of the character described, in combination, a conveyer, a plurality of bars secured together in substantial parallelism so as to leave a space between them, each bar having a plurality of goods-

supports carried thereby and detachable means for securing said bars to said conveyer.

2. In a drying-machine of the character described, in combination, a conveyer, a plurality of bars, a plate secured to both bars so as to leave a space between them, each bar having a plurality of goods-supports carried thereby and detachable means for securing

10 said plate to said conveyer.

3. In a drying-machine of the character described, in combination, a conveyer, a plurality of bars, a plate secured to both bars so as to leave a space between them, each bar 15 having a plurality of goods-supports carried thereby, a hook carried by the conveyer and an eye carried by the plate.

4. In a drying-machine of the character described, in combination, a conveyer, a plurality of bars secured together so as to leave 20 a space between each bar having a groove, a plate longitudinally movable in each groove, angular goods-supports carried by said plates, loops secured to said bars in line of movement of said goods-supports, 25 and detachable means for securing said bars to said conveyer.

5. In a drying-machine of the character de-

scribed, in combination, a conveyer, a plurality of bars, a plate secured to both bars so as to leave a space between each bar having 30 a groove, a plate longitudinally movable in each groove, angular goods-supports carried by said plates, loops secured to said bars in line of movement of said goods-supports, and detachable means for securing said plate 35 to said conveyer.

6. In a drying-machine of the character described, in combination, a conveyer, a plurality of bars, a plate secured to both bars so as to leave a space between each bar having 40 a groove, a plate longitudinally movable in each groove, angular goods-supports carried by said plates, loops secured to said bars in line of movement of said goods-supports, a hook carried by the conveyer and an eye carried by the plate. 45

In testimony of which invention I have hereunto set my hand at Philadelphia on this 24th day of June, 1903.

WILLIAM M. BARNES.
